UNITED STATES PATENT OFFICE.

WILLIAM F. TAYLOR, JR., OF PROVIDENCE, RHODE ISLAND, ASSIGNOR OF
ONE-HALF TO THOMAS D. TAYLOR, OF BOSTON, MASSACHUSETTS.

SWITCH-THROWING MECHANISM.

SPECIFICATION forming part of Letters Patent No. 748,812, dated January 5, 1904.

Application filed March 30, 1903. Serial No. 150,144. (No model.)

To all whom it may concern:

Be it known that I, WILLIAM F. TAYLOR, Jr., a citizen of the United States, residing at Providence, in the county of Providence and State of Rhode Island, have invented certain new and useful Improvements in Switch-Throwing Mechanism, of which the following is a specification.

This invention relates to certain new and useful improvements in switch-throwing mechanism adapted to be operated, preferably, by electricity through the medium of suitable means arranged either in the road-bed underground or in the case of overhead trolleys adjacent the wires thereof.

The primary object of my improvement is to provide a device of the type which will be extremely simple in construction, practical, and, further, one which at all times can be relied upon to throw the switch-point to the desired position.

Broadly, the invention comprises a pair of motors arranged in the road-bed beneath the switch-point, the same operating a train of gears, which in turn impart movement to a pivoted member, which when operated actuates a pair of cut-outs for breaking the circuits, hereinafter referred to. To the outer end of this movable member the switch-tongue is rigidly secured.

Other objects and advantages will be more particularly set forth in the accompanying description and defined in the appended claims.

In the accompanying drawings, in which like numerals of reference indicate like parts throughout the several views, Figure 1 is a top plan view of a portion of the road-bed at a point in proximity to the switch-tongue and showing in dotted lines the relative position of my improvement thereto. Fig. 2 is a sectional view taken on line $x-x$ of Fig. 1. Fig. 3 is a cross-section of the protective casing for my improvement and the mechanism arranged therein. Fig. 4 is a top plan view with the cover of the casing removed. Fig. 5 is a detail view of the segmental member, and Fig. 6 is a view taken on line $y-y$ of Fig. 2.

1 indicates the main rails, and 2 the side track. To the outer end of one of the rails

of the side track, as in the usual construction, is pivoted the switch-tongue 3.

4 indicates the casing, which, as indicated in Fig. 1, is preferably arranged directly beneath the switch-tongue. This casing is provided in its upper wall with a transverse opening 5, through which projects the rod 6, the same having its upper end rigidly secured to the switch-tongue, as clearly shown in Figs. 2 and 6, and its lower end secured by nuts or some equivalent means to the pivoted member 7. The member 7 can be pivotally mounted in any desired manner, and I for convenience have illustrated a standard 8, which is of very simple construction.

In the casing 4, at a point adjacent the end opposite to the opening 5 thereof, is arranged a pair of motors 9, the same being provided with gears 10, which mesh with an intermediate pinion 11. This pinion 11 in turn meshes with the segmental rack 12, formed integral with the rear end 7.

From the foregoing it will be obvious that as the two motors are alternately energized, so as to rotate their respective pinions, the member 7 will be oscillated through the medium of the intermediate gear 11 and rack 12, so as to operate the switch-tongue, which, as heretofore stated, is rigidly secured thereto. In order to automatically break the circuit, and thereby stop the motors from rotating when the switch-tongue has been moved to the desired point, I arrange at a point intermediate the pivotal point of the member 7 and the motors a pair of switches or circuit make and breakers, which are operated by the movable member. I will therefore proceed to describe the detailed construction thereof.

Rigidly supported upon a suitable base or standards 12^x is a casing 13, above which moves the member 7 as it is operated.

14 and 15 indicate the contacts for the switch-arms 16 and 17, respectively, which are pivoted at a point adjacent thereto and having their inner ends bent upwardly and projecting through apertures formed in the top of the casing. It is to be understood that the switch-arms are designed to be tilted as they are engaged by the movable member 7,

thus moving them against the tension of their springs and bringing them out of contact with the contact-points.

In operation as the current passes through the wires 18, contacts 15, wire 19, and motor 9 to ground 20, the motor 9 being energized to rotate, thus swinging the member 7, which when it engages the upturned arm of the switch member of that circuit will tilt the same, thus breaking the circuit and preventing further operation of the motor. The operation for swinging the member 7 in a reverse direction is practically the same, the current passing through the wire 21, contacts 14, wire 22, the other motor 9, and grounding through wire 23.

In order to prevent the upturned ends of the switch members 16 and 17 from slipping or being struck too abruptly by the member 7 as it is oscillated, I form the same with grooves 24, in which the upturned ends of the said switch members enter when they are operated.

25 indicates a slide secured to the rod 6 at a point directly beneath the slot 5 of the casing 3, the same being of greater length than and being adapted to at all times close the said openings, whereby rain and foreign substances are excluded from the interior of the 30 casing.

In the foregoing description and in the accompanying drawings I have shown the preferred form of my improvement. It will be apparent, however, that I reserve the right 35 to make such minor changes as I may see fit as fall within the scope of the appended claims.

Having thus fully described my invention, what I claim by Letters Patent is—

1. The combination with the switch-tongue 40 and the movable member secured thereto, of motors, gearing directly connecting said motors, and of which gears one engages directly with said member, and a casing inclosing said member and its actuating means.

45 2. The combination with the switch-tongue and the casing arranged adjacent thereto in the road-bed, said casing being formed with a slot, of a movable member arranged in said casing, a rod extending through the said slot 50 and secured to the switch-tongue and movable member respectively, a slide secured to the said rod for closing the opening in said casing and motors with gears intermeshing with means for operating the said member.

55 3. The combination with the switch-tongue and the movable member connected thereto, of motors, gearing between the same and the movable member and a cut-out actuated by said movable member.

60 4. In combination with the switch-tongue and the movable member, said movable member having one of its ends formed with a segmental rack, and its opposite end operatively connected to the switch-tongue, of a pinion

meshing with the toothed end of the said member, and means for operating the said pinion.

5. In combination with the switch-tongue and the casing arranged in the road-bed, of a member pivoted in the said casing and being 70 operatively connected to the switch-tongue, of a pair of motors adapted to be alternately energized for operating the said member, and means actuated by the said member for stopping the said motors from rotating. 75

6. The combination with the switch-tongue, of a member pivoted at a point adjacent thereto and having one of its ends operatively engaging the same and its opposite end formed with teeth, a pinion meshing with the toothed 80 end of the said member, electrical means for operating the said pinion, circuit make and breakers arranged in proximity to the said member and being in circuit to the said electrical means, substantially as and for the 85 purpose specified.

7. The combination with the switch-tongue and the casing arranged in the road-bed therebeneath, of a member pivoted in the said casing, and being operatively connected to the 90 switch-tongue, a segmental rack carried by the said movable member, a pinion meshing with the said segmental rack, a pair of motors, pinions operated by the said motors and meshing with the first-named pinion, a pair 95 of switches arranged on opposite sides of the said movable member and being in circuit with the said motors, said switches being adapted to be operated by the said movable member, and means for returning or closing 100 the said switches after they have been actuated by the said movable member.

8. The combination with the switch-tongue and the casing arranged in the road-bed adjacent thereto, said casing being formed with 105 an opening, of the switch-throwing mechanism arranged in the casing, one member of which projects through the said opening of the said casing and being operatively connected to the switch-tongue, and a slide secured to the said projecting member, said slide being of greater length than the said opening, and keeping the said opening closed at all times. 110

9. The combination with the switch-tongue, 115 of a pivoted member carrying a segmental rack, a pinion engaging the said rack, means for rotating the said pinion, and means actuated by the said movable member for throwing the switch-tongue, substantially as described. 120

In testimony whereof I have affixed my signature in presence of two witnesses.
